and have the advantage of being able to be used in a manner which is safe and effective and which is particularly adapted for use in trimming the hair of the head.

Another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

Still another object of the present invention is to provide a device which is particularly adapted for use in trimming the hair of the head and which is safe and effective and which is particularly adapted for use in trimming the hair of the head.

UNITED STATES PATENT OFFICE

2,615,243

HAIR TRIMMER

Royce M. Brown, Albuquerque, N. Mex.

Application May 15, 1950, Serial No. 161,983

2 Claims. (Cl. 30—30)

2

beyond said cutting edge, and an upstanding centrally disposed longitudinal rib carried by said base and constituting a finger-grip.

Other objects and features such as simplicity of construction, will become apparent in following the description of the illustrated forms of the invention.

In the drawings:

Figure 1 is a plan view of one form of the invention;

Figure 2 is a side view of the device in Figure 1;

Figure 3 is a sectional view taken substantially on the line 3—3 of Figure 2 and in the direction of the arrows, everything being omitted except one tooth which is shown in section;

Figure 4 is a plan view of a blade used in connection with the device;

Figure 5 is a plan view of a second form of the invention, and;

Figure 6 is a longitudinal sectional view taken substantially on the line 6—6 of Figure 5 and in the direction of the arrows.

Reference is first made to Figures 1—4. Here a base 10 is provided of any suitable material and has a forwardly opening passage 12 therein. This passage is adapted to accommodate the blade 14 of special design (Fig. 4), with the cutting edge extending to the forwardmost position of the base. A blade holder 16 having a finger grip 18 extending from one end, is pivoted at the other end by means of the screw 20, which passes through the passage 12. The screw is passed through a notch 22 at one end of the blade 14 and the other end of the blade has another notch 24 forming a seat for the locking pin or screw 28 which is secured to the body or base 10 and which passes through the passage 12. The screw 20 passes through the passage at one end thereof, while the screw 28 passes through the passage at the other end thereof.

A finger holding member 30 rises from the base and has a finger receiving recess 32 on one upper edge thereof and a finger receiving recess 34 on a lower edge thereof. The device is of such size that it is adapted to be held in one hand by two or three fingers while it is being passed over the skin of the individual whose hair is to be cut.

There is a smoothly curved surface forming a cam 36 at the rear bottom part of the base 10.

This cam surface serves as a rocking surface as the device is moved through the hair of the individual in order to provide the necessary shingling of the hair.

In order to assist in the proper cutting operation, there are special teeth provided. Any num-

ber of teeth may be used as considered practical. There are seven teeth provided in Figure 1, this number being chosen merely for illustrative purposes. The teeth are arranged so that the leading points thereof are staggered, as is evident from the plan view in Figure 1. Each tooth is substantially triangular in cross section, for example the tooth 38 in Figure 3, and the teeth have each side tapering toward the front thereof. By this construction the bottom surfaces of each tooth (Fig. 2) are swept upwardly or upwardly inclined to provide a second bottom cam surface for smoothness of operation.

Reference is now made to Figure 5. There is a base 50, in this instance the base being provided of an upper section 52 and a lower section 54. The base is provided with a smoothly curved cam surface 56 which is equivalent to and which serves the same purpose as the cam surface 36. The teeth of this form of the invention are shaped similarly to the teeth of the first described form of the invention, however there are upper teeth 58 provided at the leading or front edge of the upper section 52. The lower teeth taper as they project forwardly of the base so that there is the inclination forming the front cam surface below the teeth of the bottom section 54, as in the embodiment of Figure 1.

A finger gripping member 60 rises from the upper section 52 and has a finger recess 62 in one upper edge thereof.

A passage 62 is formed between the sections 52 and 54 in order to accommodate the small blade 64 which is disposed therein, the forward edge of the blade projecting forwardly but stopping behind the front pointed parts of the teeth. A screw or similar fastening element 66 is passed through openings in the sections 52 and 54 in order to hold the two sections together thereby forming the jaws to retain the blade 64 in the passage 62.

The operation of this form of the invention is identical to the operation of the previously described form.

This trimmer may be used, after first dampening the hair with warm water, and the trimming operation may well be begun in front of the ear, at the extreme bottom or lower edge of the hair, and proceed by pushing the trimmer upwards and into the hair against the lay or grain of the hair. At the beginning of the operation the front of the trimmer is held down tight against the skin, but as it proceeds upward you gradually relax this pressure to leave the stubble of the hair longer as you proceed higher. As it nears the crown or upper part of the head, the teeth are permitted to finally rise to such an ex-

tent that the tips are out of the hair and the cutting operation is completed in that particular area.

Having described the invention, what is claimed as new is:

1. A manually actuatable self-servicing hair trimmer adapted to be held in the user's hand and advanced by way of a predetermined path from a low toward a high position to, in this manner, clip the hair shafts in a direction from their free outer ends toward their inner rooted ends comprising a scalp contacting base plate having an oblique leading edge with forwardly projecting teeth all of said teeth being the same in length, pointed and triangular in cross-section and having their pointed ends on a line which corresponds in obliquity with the obliquity of said leading edge, a blade assembling and clamping plate superimposed upon and separably fastened to said base plate and provided with a central axially disposed finger grip, and a cutting blade interposed between said plates and secured therebetween, the cutting edge of said blade and leading edge of said clamping plate both being oblique and having their obliquities corresponding with the first-named oblique edge.

2. The structure specified in claim 1, wherein the leading edge of the clamping plate has teeth with the terminal ends thereof spaced inwardly of the cutting edge of said blade, the intermediate area of the bottom of said base plate being flat and the trailing edge being convex and constituting a fulcrumming shoe.
